[57] CLAIM

The ornamental design for a liquid soap container, as shown and described.

DESCRIPTION

FIG. 1 is a perspective view of a liquid soap container showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIGS. 8, 9, and 10 are perspective views thereof, with the broken-line disclosure of additional, identical components assembled being for illustrative purposes only and forming no part of the claimed design.
